UNITED STATES PATENT OFFICE.

LEO M. MOSER, OF MOSCOW, IDAHO.

ARMORED CAR.

1,302,577.

Specification of Letters Patent.

Patented May 6, 1919.

Application filed January 2, 1918. Serial No. 209,886.

To all whom it may concern:

Be it known that I, LEO M. MOSER, a citizen of the United States, residing at Moscow, in the county of Latah and State of Idaho, have invented certain new and useful Improvements in Armored Cars, of which the following is a specification.

The present invention relates to improvements in armored cars, of the "tank" type, and is designed to provide certain improved features whereby the heavy and ponderous automobile may be navigated, or steered with despatch, thus rendering its movement of comparative flexibility and at the same time increasing its effectiveness by providing a great radius of action while on the offensive in warfare.

The invention involves, essentially an armored car or tank of peculiar construction and arrangement whereby the car itself is supported on the propelling mechanism as a foundation, when traveling, as is usual, but when stationary, the car is designed to support not only itself, but also the propelling mechanism, as will be hereinafter more fully explained and set forth in the appended claims.

In the accompanying drawings one complete example of the physical embodiment of the invention is illustrated, built and arranged according to the best mode so far devised for the practical application of the principles of the invention, but it will be understood that colorable changes and alterations may be made in the apparatus within the scope of the claims without departing from the spirit of the invention.

Figure 1 is a sectional view of the armored part of the car, showing the propelling mechanism and other parts in elevation, and with the body of the car supported on the propelling mechanism.

Fig. 2 is a view similar to Fig. 1 showing the outside of the car.

Fig. 3 is a view similar to Fig. 1, partly in section, but with the car supported upon itself and also supporting the propelling mechanism off the ground.

Fig. 4 is a partial sectional detail view showing the ball bearing upon which the platform of the apex portion of the conical armored car may rotate with relation to the base portion of the car, which base is in the form of a truncated cone.

Fig. 5 is a detail of the ball bearing between the apex portion and base portion of the conical armor of the car.

Fig. 6 is an enlarged detail view of one of the locking detents to hold the conical armor of the car against rotation with the main frame and deck of the car.

In the preferred form of the invention the armor for the car is conical in shape approximately as shown in the drawings in order to best dispose of shells or projectiles which may be fired at it, and the base portion of the armor is indicated at 1 as a truncated cone made of a suitable thickness of steel plates designed for the purpose, and fashioned with an enlarged, annular bead 2 at its upper edge in which a circular groove 3 is provided, and a ball race 4 is finished at the base of the groove for the balls or series of bearing balls 5 forming a race. At its lower edge, the base is flared outwardly and turned or curled over, as at 6, to perform the function of an apron or guard preventing the enemy from securing a hand hold for the purpose of toppling the car over, and the fixed bottom 6', flush with the lower edge of the base, also assists in guarding the interior of the car from intrusion from the outside.

Above the base, the apex portion 7 of the cone, is rotatable with relation to the base, and to enable independent rotation of the apex, the lower edge 8 thereof rests upon the ball race 5 at the upper part of the base and permits rotation of the apex portion upon the base portion when desired.

The main frame of the car is indicated at 9 and has fixed thereon a gun deck 9' of suitable and proper construction, preferably circular in form, and supporting a hydraulic lifting jack which comprises the fixed cylinder 10 supported from the frame by the tripod base 11, and operated, as is the entire operating and actuating mechanism of the car, from the motor or engine 12, the hydraulic jack being controlled directly by the governor 19, directly at its side.

The hollow piston 13 which operates as a plunger in the cylinder, supports the rotatable platform 14, which has a pintle 14' seated in the hollow end of the piston so that it may move synchronously with the apex of the cone, when it is rotated through the instrumentality of the head 14' and ball bearings 14" (see Fig. 4).

In Fig. 6 is best shown the means of holding the armored portion of the car rigid with the base frame and deck 9', a retaining detent 15 being pivoted at 16 on the armored wall and adapted to engage a notch 17 in the edge of the deck, and a latch 18 is

provided to hold the detent out of operative position when desired. There are several of these detents spaced about the periphery of the deck, at equal intervals, so that the detents may be made to engage any of the notches. Thus when it is desired to revolve the car, when in position of Figs. 1 and 2, it will readily be seen that the detents may be disengaged, and retained in inoperative position. The conical armor is supported from the piston by the radial arms or braces R, located just below the ball bearing which supports the upper platform 14, and the piston is free to revolve in its cylinder which is in turn supported from the tripod base on the gun deck and frame. The propelling mechanism, which is supported from the main frame, is of the caterpillar type, and includes the sprocket chains 20 and sprocket wheels 21, the latter journaled in the truck frame 22 in the usual manner, and the propelling mechanism is driven by power transmitted from the motor or engine 12 in well known or approved manner. The bottom or base plate 6 forming a closure for the car is open, as at 6^a for the passage therethrough of the caterpillar propelling devices, and spring braces 23 are employed to lend comparative rigidity to the deck of the car and absorb shocks, by bearing against the base plate and receiving and cushioning any pivotal movement between the armored shell of the car and the rigid main frame. The armored shell is provided with suitable port holes 25 for the guns 26, which are the usual rapid fire or automatic firearms, and the portion, which may be designated the front of the car, is fashioned, on its exterior surface, with sharp cutting edges or serrated portions 27 for cutting wire barricades, etc.

The above described construction renders the armored car very facile in all its movements. For instance, assuming the car to be arranged as in Figs. 1 and 2 and traveling toward the front, it will readily be seen that the shell of the car may be manually revolved bodily, or only the apex may be revolved, or both be revolved, as desired, to bring the guns to bear at certain points. The gun may be withdrawn from the port hole 25, and the apex may be manually revolved, with relation to the platform and frustum or frustoconical shell, when desired. If it is necessary to stop, the car is brought to a standstill, and then, through the instrumentality of the hydraulic jack, the shell is lowered to the ground, with the base plate resting directly on the ground, as in Fig. 3, and by continued action of the jack, the propelling mechanism and main frame are

lifted entirely free from the ground, as in Fig. 3. In this condition a defensive warfare may be maintained, and it will be apparent that the interior of the car is entirely shut off from intrusion from the exterior. Now should it be desired to change the course of travel of the car, as for instance in a retreat, the detents 15 are disengaged, and the deck 70 and propelling mechanism are revolved within the shell as a support, either to an angular position, or to the exact reverse position, and the engine started. The jack again lifts the shell off the ground and thus 75 shifts the weight of the entire apparatus to the main frame and propelling mechanism, and the car may thus be manipulated and navigated with exceeding great mobility.

The accompanying drawings illustrate the 80 necessary elements and features of construction of the car, the details of construction being omitted, as are also some of the parts of the driving, propelling, and transmission mechanism, which are not necessary to a 85 complete understanding of the invention as disclosed.

What is claimed herein is:—

1. In an armored car, the combination with a main frame and a shell revolvably supported thereon and having a base plate and propelling mechanism, of means for bodily raising the main frame and propelling mechanism within the car while the shell is bodily supported through its base 95 plate on the ground.

2. The combination with a main frame and propelling mechanism, of a frustoconical rotatable shell having a rotatable apex and an open base plate to accommodate the 100 propelling mechanism, and means for transferring the weight of the entire apparatus to the shell by lifting the frame and mechanism from the ground.

3. In an armored motor car the combination with a main frame and propelling mechanism, of an inclosing shell supported by the frame and having an open base plate to accommodate the propelling mechanism and means for transferring the weight of the 110 frame and mechanism to the shell and supporting them thereby.

4. The combination in an armored motor car with a main frame and deck thereon, and propelling mechanism, of an upper platform revolvably supported on the platform frame and a revolute frusto-conical shell, means on said shell co-acting with the deck to lock the shell, means for elevating the platform, and said shell having an open base 120 plate to accommodate the propelling mechanism.

In testimony whereof I affix my signature.
LEO M. MOSER.
